UNITED STATES PATENT OFFICE

2,444,173

ELECTRONIC EPILATOR

Henri E. St. Pierre, San Francisco, Calif.

Application July 27, 1945, Serial No. 607,383

8 Claims. (Cl. 128—355)

1

The present invention relates to improvements in an electronic epilator wherein controlled high frequency oscillations and a stabilized and balanced direct current, separately or superimposed one upon the other and connected to a single active electrode or needle, operate in conjunction with a high frequency inductive pad or electrode and a dispersive electrode, to coagulate and decompose a hair follicle by electrolysis for permanent epilation of superfluous hair.

In the use of electronic devices for diathermy and particularly as an epilator, extensive apparatus is usually required. The power output must be regulated so that the action will accomplish the result without injury to the patient or leaving noticeable scar tissue, but when so regulated, the percentage of hair killed is less per area treated per treatment than that accomplished by the present invention, and requires repetitive treatment to accomplish the same percentage of hair killed accomplished by a single treatment disclosed herein. It has been found that by the use of apparatus of the present invention, speed of treatment has been accomplished and the percentage of kill per individual treatment has been greatly increased without any sacrifice of safety to the patient or damage to the skin and with a minimum of discomfort and scar tissue. Accordingly, it is an object of the present invention to provide a new and improved electronic epilator for the safe and speedy permanent removal of superfluous hair.

Another object is to provide a new and improved device of the character set forth having a greatly simplified and economically operated construction for quickly and harmlessly destroying hair follicles or bulb roots by electrolysis, coagulation and desiccation.

The use of high frequency currents provides the speed of result desirable in the operation, but is painful to the patient and is very apt to leave extensive scar tissue if a high percentage of hair kill is maintained. It has been found that by using both controlled high frequency oscillations and a stabilized and balanced direct current (which may be regulated independently) through a single needle only, the operator may give much closer attention to the operation than is possible with multiple needles, without any sacrifice of speed. The result is fast and safe for the patient. A further object, therefore, is to provide an electronic epilator wherein a diathermy type of high frequency generator and a direct current power supply are interconnected to allow the output of one to be superimposed

2

upon or blended with the other so that either or both are available to a single active electrode operating in conjunction with a high frequency inductive electrode, or a dispersive electrode, or both, to permanently kill hair in the first treatment in more than three-fourths of the subject follicles, and to provide such an instrument which will operate without undue injury or discomfort to a patient and without noticeably permanently scarring the adjacent cuticle. No other known devices can be operated to produce such a high percentage of kill per treatment with such speed and safety.

It has likewise been found in the use of devices of the present invention wherein high frequency generators and a direct current power supply may be controlled independently or blended at will, and where they are interconnected to a common active electrode, that no charring or cauterization ensues. Thus it is a further object to provide a new electronic epilator for high frequency and direct currents so interconnected one with the other that the several benefits of each may be simultaneously or alternately applied for the maximum removal or kill of superfluous hair per treatment, without undue injury to the adjacent cuticle or discomfort to a patient.

Further objects are to provide a construction of maximum simplicity and ease of assembly and such further objects, advantages, and capabilities as will appear from the device and invention described herein. The invention further resides in the conventional construction and arrangement of parts illustrated in the accompanying drawings and while there is shown therein a preferred embodiment, it is to be understood that the same is merely illustrative of the invention and that the invention is capable of modification and change and comprehends other details of construction and arrangements without departing from the spirit or the scope of the appended claims.

Referring now to the drawings:

The single figure of the drawings shows two circuits set off in dotted rectangles, the high frequency generator being indicated by the rectangle A and the direct current circuit being indicated by the dotted rectangle B. The high frequency generator indicated as A comprises a diathermy type of circuit in which 1 and 2 represent the line wires or source of energy leading to a filament voltage source from a 110 volt transformer 3, connected inductively to high frequency transmitter tubes 4 and 6, which are, in turn, connected to a combination of a coil 8

and a condenser 10. This combination of inductance and capacitance operates as an oscillator and produces an oscillatory circuit to inductively excite a vario coupler 12, one side of which is connected to an active electrode or needle 14, while the other side is directly connected to an insulated diathermy pad 16 for inductive coupling to a patient.

To further balance and stabilize this current, lines 18 and 20 lead from the transmitters or wave rectifying tubes 4 and 6, after transposition to nullify undue reactance, to opposite portions of coil 8, each line 18 and 20 being further damped, preferably by mica condensers 22 and 24, respectively. This highly stabilized and balanced oscillatory current may be controlled through a power supply input 26 and the circuit may be grounded as at 28.

The alternating current rectifier within the dotted rectangle B also has lead-in wires 30 and 32 from 110 volt alternating current source to a step-up transformer 34, coupled to a full-wave rectifying tube 36, producing a stable and well rectified direct current. The output of this unit is controllable independently of the high frequency circuit and has the positive side directly connected to a patient through a passive or dispersive electrode 38.

The direct current is also further rectified and stabilized by iron-core filter chokes 40 and 42 between the transformer 34 and a fixed resistor 46, with a control or a rheostat 48 from which a line 52 leads through a high frequency choke 54, preferably an air-choke, to the active electrode or needle 14.

Further stabilizing of the direct current is accomplished by the filter condensers 56 and 58 between the transformer 34 and the dispersive electrode 38 and arranged to control the direct current output to the active electrode or needle 14 with which it is directly connected.

In operation, either the insulated diathermy or inductive pad 16 or the direct dispersive pad 38, or both, may be applied to a patient, after which the point of the active electrode or needle 14 is introduced into the hair follicle (not shown) of the hair to be removed. This completes a stabilized and highly balanced high frequency circuit superimposed upon and blended with or modified by the direct generator B so that the sudden development of heat within the subcutaneous area immediately adjacent, which normally causes the undue discomfort and perhaps permanent injury to a patient, will be prevented, while the very small area of the hair follicle or hair bulb (not shown) will be instantly coagulated to an extent which will permanently destroy the hair growth. The pick-off 12 of the high frequency generator A operated independently or in conjunction with the rheostat 48 will at all times operate to alter and control the superimposed and blended or balanced currents to meet varying conditions required for the various individual patients.

I claim:

1. An epilator comprising a source of high frequency electrical current; a generator producing a stabilized direct current; and an electrode common to said high frequency and stabilized direct current.

2. An epilator comprising a source of high frequency electrical oscillations; a generator producing a well stabilized direct current; an active needle electrode connected to both currents and oscillations; and control means for regulating the amount of either current passing to said needle electrode.

3. An epilator comprising a source of high frequency electrical oscillations; dampening means for said oscillations; a generator for producing a stabilized direct current; an active needle electrode operatively connected to said oscillations and direct current; and separate means for checking said direct current.

10 4. An epilator comprising a source of high frequency electrical oscillations; means for controlling the output of said oscillations; a generator producing a stabilized direct current; separate controlling means for said direct current; an active needle electrode connected to said oscillations and direct current; an insulated diathermy pad connected to the high frequency oscillations for inductive coupling to a patient; and a dispersive electrode connected to the direct current.

15 5. An epilator comprising a high frequency current; condenser means in said high frequency current; inductance means with high frequency pick-off operatively connected with said high frequency current; an insulated diathermy pad, for inductive coupling to a patient, connected on one side of said pick-off; an active needle electrode connected to the opposite side of said pick-off; a generator for producing a highly stabilized direct current connected to said active needle electrode; control means for regulating the output of said direct current; and a dispersive electrode connected to said direct current.

20 6. In the method of removal of superfluous hair, the step of superimposing a stabilized direct current upon a high frequency current leading to a single active electrode.

25 7. A diathermic method including the step of controllably blending the output of a stabilized direct current with a source of high frequency oscillations, both in circuit with a common active electrode.

30 8. In the method of removal of superfluous hair the step of controllably blending a stabilized direct current with a source of high frequency oscillations, the output of both leading to a common active electrode.
